UNITED STATES PATENT OFFICE.

FRANK CARTLIDGE, OF TERRE HAUTE, INDIANA, ASSIGNOR TO SULLIVAN MACHINERY COMPANY, A CORPORATION OF MASSACHUSETTS.

MINING MACHINE.

Application filed June 5, 1916. Serial No. 101,687.

To all whom it may concern:

Be it known that I, FRANK CARTLIDGE, a citizen of the United States, residing at Terre Haute, in the county of Vigo and State of Indiana, have invented a new and useful Mining Machine, of which the following is a specification.

It is the object of my invention to provide an improved feeding mechanism, particularly for mining machines, whereby great flexibility in feeding is obtainable, and whereby the machine being fed may be moved at any desired speed in any direction and made to move with a straight or turning movement as desired; and to obtain this flexible feeding from a single source of power, which also drives the cutting or other operating mechanism of the machine.

The accompanying drawings illustrate two embodiments of my invention. Fig. 1 is a plan view, partly in section, of a mining machine embodying one form of my invention; Fig. 2 is a side elevation of such mining machine, with some parts in section; Fig. 3 is a section on the line 3-3 of Fig. 1; Fig. 4 is a plan view showing the gear connections for the feeding mechanism; Fig. 5 is an enlarged section through the paying-out drum shown at the right of Figs. 3 and 4, and is taken on the line 5-5 of Fig. 4; Fig. 6 is an elevation of the winding drum shown at the right of Fig. 3, illustrating how it is thrown into and out of action; Fig. 7 is a plan view similar to Fig. 1 showing the mining machine equipped for feeding by means of a feed chain, this being the form elected for prosecution in the present case; Figs. 8, 9, 10 and 11 are diagrammatic views showing the flexible connections for different feeding operations, the machine shown in these views being of the cable type and the views respectively showing the machine unloading from a truck, dumping, cutting across a face, and moving back to the truck after the cut is finished; and Figs. 12, 13 and 14 are diagrammatic views showing the feed chain form of mining machine illustrated in Fig. 7 in various positions which may be assumed for different reasons during cutting across a face. The proportions of parts may obviously vary and uniformity of dimension has not been adhered to rigidly in all the views.

The main frame 15 conveniently has a

flat bottom for sliding on the mine floor, and is provided with a projecting arm 16 which carries and guides the cutter chain 17 provided with the cutters 18, in the usual manner. This cutting chain is driven by a driving sprocket 19 mounted on a vertical shaft at the opposite end of the frame 15 from that from which the arm 16 projects. Fixed on the same shaft is a gear 20, the upper face of which is cup-shaped for economy of space, and this gear 20 meshes with a pinion 21 on the lower end of a vertical shaft 22 on the upper end of which is fixed a bevel gear 23 meshing with the bevel driving pinion 24 on the shaft of the operating motor 25, which is most conveniently an electric motor. The upper and lower ends of the shaft 22 are supported in two bearings, beyond the gears 21 and 23.

A worm 26 is fixed on the shaft 22 between the gears 21 and 23, and meshes with a worm wheel 27 on a horizontal shaft 28, from which the feeding mechanism is driven. The shaft 28 carries a pair of driving pinions 29, which mesh with a pair of gears 30 mounted on sleeves 31 and 32 respectively, which sleeves are co-axial with and rotatable relatively to a horizontal shaft 33, the sleeve 31 fitting directly on a bushing on the shaft 33. The two gears 30 are spaced apart, but are connected to rotate together by bolts 34, on each of which bolts are mounted two planet gears 35 and 36 of slightly different size but rigid with each other so as to rotate together. The gears 35 are shown as slightly larger than the gears 36. The planet gears 35 mesh with a sun gear 37, and the planet gears 36 with a sun gear 38, the sun gear 38 being larger than the sun gear 37 to correspond with the difference in size of the planet gears 35 and 36. The reason for having the pinions 29 and gears 30 duplicated is merely to eliminate all tendency to twist in the planet gears 35 and 36 and the sun gears 37 and 38. The sun gear 38 is fast on the shaft 33. The sun gear 37 forms part of a sleeve 39 rotatably mounted on said shaft 33 and located between such shaft and the sleeve 32. A sliding sleeve 40 has slidable toothed engagement with the sleeve 39, and is slidable in either direction along such sleeve by a finger 41 which may be operated by a shift lever 42. The sleeve 40 is provided with clutch teeth at both axial ends, so that when

slid in one direction from neutral position, in which it is free from any locking engagement, the teeth 43 on one end engage teeth 44 on the end of the sleeve 32, to lock together the sleeves 32 and 39 and thus cause the sun and planet mechanism to rotate as a unit; and when slid in the other direction from neutral position the teeth 45 on the other end of such sleeve 40 engage teeth 46 on a brake wheel 47 loosely mounted on the shaft 33 and co-operating with a brake band 48 which may be set or released by an operating handle 49 to hold stationary or permit any desired slipping of the brake wheel 47.

The shaft 33 drives both a feed operating member herein in the form of a winding drum 50 and a co-operating feed operating or controlling member herein in the form of a paying-out drum 51, shown at the left and right hand sides of Fig. 3 respectively. For driving the winding drum 50, it is provided at its left hand end (Figs. 3 and 4) with a driving pinion 52, which meshes with an internal gear 53 on such winding drum. The winding drum is mounted on an eccentric bushing 54 in turn mounted on a stub shaft 55, around which it is adjustable by an operating handle 56 to shift the gear 53 into and out of mesh with the pinion 52.

For driving the paying-out drum 51, the shaft 33 has keyed on its right hand end (Figs. 3, 4, and 5) a sleeve 57 which at its inner end is provided with gear teeth to provide a sun gear 58 and at its outer end forms a bearing surface for a rotatably mounted sleeve 59 which carries a plurality of planetary gears 60 which mesh with the sun gear 58 and with an internal gear 61 on the inside of such paying-out drum 51. The pins 62 on which the planet gears 60 are mounted are carried at their right hand ends in the sleeve 59, and on their left hand ends carry a brake wheel 63, with which co-operates a brake band 64 which may be set or released by an operating handle 65 to hold stationary or permit any desired slipping of the brake wheel 63. The sleeve 59 has an outer annular portion 66 between which and the main portion of the sleeve is an annular space into the inner portion of which projects an inner annular member 67 of the paying-out drum 51, the member 67 having a bearing on the sleeve 59 and thereby furnishing the support for such paying-out drum. The outer surface of the annular member 67 and the inner face of the annular portion 66 are toothed to engage with alternate ones of a series of clutch disks 68 which are located between the parts 66 and 67. The outer end of the sleeve 59 is threaded, and has mounted thereon a clutch-setting nut 69 provided with an operating ring 70 by which it may be moved annularly to engage with greater or less pressure the

web by which the paying-out drum 51 is mounted on the annular member 67, so as to cause more or less firm interengagement of the clutch disks 68. It should be noted that the teeth of the internal gear 61 are of such length and the parts of such construction that a certain degree of movement of the drum 51 longitudinally of the shaft 33 is permitted.

At this point it should be noted that the drum 51 is smaller than the drum 50, but by reason of the reduction occasioned by the driving of the drum 50 through the pinion 52 and internal gear 53, the drum 51, when the operating ring 70 is moved to effect the locking of the parts as later explained so that the drum 51 rotates at the same angular rate as the shaft 33, will have a greater peripheral speed than the peripheral speed of the drum 50. On the other hand, when the drum 51 is driven at the reduced rate which is accomplished by driving the internal gear 61 through the planet gears 60 and sun gear 58 the peripheral speed of the drum 51 will be less than that of the drum 50 and, moreover, the drum 51 will rotate in the opposite direction to drum 50.

The winding drum 50 and the paying-out drum 51 may be equipped for winding ropes or cables 72 and 73 respectively, as shown in Figs. 1, 3, 4, 5, 8, 9, 10, and 11, in which case the excess of cable is preferably wound up on the drums for storage and the two cables 72 and 73 are preferably entirely separate; or may be equipped for winding chains 74 and 75 respectively, as shown in Figs. 7, 12, 13 and 14 in which case there is ordinarily but a fractional turn of the chain on each feed operating member and the two chains may be interconnected by a bight 76 having sufficient slack to permit the necessary independence of action of the feed operating members 50 and 51. The cables or chains may be carried through suitable guide blocks 77, at the desired locations, and over pulleys 78, 79, 80, and 81, or some of them, at the four corners of the frame 15, and over a pulley 82 between the pulleys 78 and 79. These various pulleys, or such of them as desired, may have swinging or a swivel mounting, as clear from Fig. 1. By means of these various pulleys, the ropes or cables may be carried from the drums in any direction from the frame 15, as exemplified in Figs. 8 to 11 inclusive, for getting different directions of movement.

In order to keep the parts properly lubricated, and free from the dust which always exists in a mine, the gearing connecting the motor 25 to the shaft 33 is enclosed in a dust-proof, oil-tight casing 84, which completely encloses such gearing. The under side of this casing, beneath the gears 30, 35, and 36, projects into the hollow upper

face of the gear 20. This casing 84 is kept partly filled with oil, which overflows along and lubricates the shaft 22. The gears 20 and 21, the sprocket 19, and part of the cutter chain are partially enclosed by the frame 15; which is open at the end, however, so that the arm 16 and the rest of the cutter chain will project therefrom. The gearing connecting the shaft 33 and the paying-out drum 51 is substantially enclosed by the web carrying such drum and by the brake wheel 63, as clear from Fig. 5.

In operation, the motor 25 drives the cutting chain 17 continuously through the driving connection already set forth, as long as the motor is supplied with the current. The motor 25 also drives the gears 30 continuously, through the bevel pinion 24, bevel gear 23, worm 26, worm wheel 27, shaft 28, and pinions 29, and the rotation of the gears 30 causes the planet gears 35 and 36 to travel around the axis of the shaft 33. If the parts are in the position shown in Fig. 3, this travel of the planet gears 35 and 36 is without effect on the shaft 33, and produces no movement of either the winding drum 50 or the paying-out drum 51; because the gear 37, which may be called the main reaction gear, is free to rotate, and so there can be no reaction against it to cause a movement of the shaft 33, which is subjected to the resistance offered to the feeding of the machine by either of the drums 50 and 51.

If a quick feeding is desired, as for moving the machine from place to place or setting it, the shift lever 42 is thrown to cause intermeshing of the teeth 43 and 44, thus locking together the sleeves 32 and 39, and causing the sun and planet mechanism connecting the pinions 29 and the shaft 33 to rotate as a unit, and such shaft 33 to rotate at the same speed as the gears 30. The actual feeding at a rapid rate may now be obtained from either the drum 50 or the drum 51, but the more rapid feeding can be obtained from the drum 51, since by reason of the gearing 52-53 the drum 50 must rotate more slowly than the shaft 33, while if the nut 69 is tightened so as to clamp together the clutch disks 68 (the brake band 64 being released) the drum 51 rotates at the same speed as the shaft 33. Under these circumstances both drums rotate in the same direction as the shaft 33. Illustrations of this rapid feeding from the drum 51 are shown in Figs. 8 and 11. Fig. 8 shows the cable 73 from the drum 51 extending from such drum over the pulley 78, behind the pulley 81, and behind the pulley 85 to a dead man 86, so that by the operation of the motor and the winding of the drum 51 the whole machine is drawn directly forward to the desired position, being first slid off the truck 87 on which

it is conveniently transported from place to place in the mine and then slid over the mine floor. Fig. 11 shows the cable 73 from the drum 51 extending from such drum over the pulley 78 and around the pulley 82 to a dead man 88, so that by the operation of the motor and the winding of the drum 51 the whole machine is drawn directly backward, first over the mine floor and then on to the truck 87. When this rapid feeding is being done by the drum 51, the operating handle 56 may be turned to the other position from that in which it is shown in Fig. 6, so as to shift the gear 53 out of mesh with the gear 52, thus making it unnecessary for the motor to move the drum 50. In the same way, if the rapid feeding is being obtained by the drum 50, the nut 69 may be loosened to release the clutch 68, and the handle 65 operated to release the brake wheel 63 from the brake band 64, so as to relieve the motor of the necessity of driving the drum 51.

If a slow feeding is desired, the shift lever 42 is thrown to cause intermeshing of the teeth 45 and 46. Then the travel of the planet gears 35 and 36 tends to produce movement of the sun gears 37 and 38 in opposite directions; the sun gear 38 tends to drive the shaft 33; and the sun gear 37, which is the main reaction gear, tends to drive the brake wheel 47. The speed of the shaft 33 may now be controlled by the setting of the brake band 48 by its operating handle 49, the maximum slow speed of the shaft 33 being obtained when the brake band 48 holds the brake wheel 47 stationary. The direction of rotation of the shaft 33 at this slow speed is in the same direction as it was at the high speed, and a slow speed feeding may now be obtained by either drum 50 or 51, as before, to produce, for instance, the final setting of the machine for starting operation. The feeding by the drum 51 may be obtained with the cable 73 wound in either direction thereon, the nut 69 being set and the brake band 64 released if the cable 73 is wound on the drum 51 in the direction shown, and the nut 69 being released and the brake band 64 set if such cable is wound on the drum 51 in the opposite direction. The feeding with this latter setting of the parts, and the cable 73 wound in the opposite direction from that shown, may also be obtained with the shaft 33 turning at high speed, as already described, which will produce a relatively high speed feeding, though slower than the "quick feeding" first described.

The actual cutting operation of the machine may now be considered. Sumping may be accomplished by means of either or both cables 72 and 73, depending upon the conditions encountered. When the ca-

ble 73 alone is employed, it may be reeved as indicated in Fig. 9 and under certain conditions of cutting the sumping cut can be accomplished by this one cable alone. It will be observed that the motor need not be reversed from its direction of operation during the unloading of the machine and that with the elements of the friction clutch 68 clamped tightly together there will be a sumping movement of the mining machine at a speed greater than its speed of movement across the face during cutting due to the fact that the winding speed of the drum 51 is at this time greater than that of the drum 50 when the latter is moving the machine across the face. If conditions indicate the desirability of such a procedure, the cable 72 may be employed simultaneously with the cable 73 during sumping, this cable being extended about a jack 91 adjacent the rib and thence laterally across the face to a jack 89. It will be understood that with the lever 56 in the position shown in Fig. 1, the drums 50 and 51 will both be winding in and, depending upon the angle of the machine to the face, it may be necessary to slip the friction 68 because the drum 51 is winding in the cable 73 faster than the drum 50 is winding in the cable 72. It will be noted, however, that the higher winding speed of the drum 51 will enable the machine to be straightened up relative to the face as the sumping progresses. Sumping would also be possible by the use of the cable 72 and drum 50 alone, the sumping speed then being slower than that which could be accomplished when the drum 51 is used together with the cable 73 as the sumping agency. Under still further circumstances, the cable 73 might pass inside the sprocket 81 during sumping and thence to a jack 90. Still a further mode of sumping is possible by reversing the direction in which the rope 72 is wound upon the drum 50 so that the rope 72 is paid out as the rope 73 is wound in. Under such circumstances, the machine would be initially inclined at a substantial angle to the rib with the end of the bar in the corner formed by the rib and face. If the cable 73 is wound in and the cable 73 paid out, the machine will simultaneously sump in and straighten up to the face. A further obvious mode of sumping which is possible is to rely mainly upon the drum 51 and rope 73, but to have the rope 72 and drum 50 available for, and under certain conditions using it for, effecting certain angling movements of the machine during sumping. This method also has the substantial advantage of permitting the tail rope 73 to be fixed to its jack or take-up member 90 and the rope 72 to be fixed to its jack 89 at the beginning of the sumping cut and the machine at the completion of

the sumping cut to go across the face without any necessity for changing the position of the jacks. In sumping according to this method, the tail rope 73 is connected as shown in Fig. 9, while the feed rope 72, instead of passing about the member 91 as shown in Fig. 9, passes directly from the guide sheave 80 to the jack 89. The handle 56 is then thrown to a position to release the drum 50 and the machine is sumped in by means of the drum 51 winding in the member 73. Should there be any tendency for the machine to assume a position perpendicular to the face prematurely, the handle 56 may be thrown in momentarily to cause the member 72 to be drawn in, thereby angling the machine slightly, the frequency with which this operation takes place depending entirely upon the particular circumstances and perhaps being wholly unnecessary. In any event, however, at the completion of the sumping cut, by throwing in the member 56 and releasing the friction 68 while tightening the brake band 64, the operator may cause the machine to proceed across the face without any change in the position of the extremities of the flexible feed operating members. Other modes of sumping will readily present themselves to those who are skilled in this art.

After the cutter chain has thus penetrated the wall for its full working distance, it must be fed along the wall so as to produce the desired cutting, as clear from Fig. 10. The cables 72 and 73 are connected in the same manner as for the arrangement shown in Fig. 9, save that as the cutting advances the dead men 89 and 90 must of course be shifted if the cut is a long one. For this operation, however, the cable 72 is wound up on the winding drum 50, and the cable 73 is paid out from the paying-out drum 51. For doing this, the shaft 33 is driven at the slow speed, as explained above, its actual speed being determined by the setting of the brake band 48. The winding drum 50 is thus operated at a correspondingly slow speed, in the same direction as is the shaft 33. The clutch-setting nut 69 is released so as to render the clutch 68 inoperative, and the operating handle 65 is turned to set the brake band 64 more or less firmly. By reason of the setting of the brake band 64, the rotation of the shaft 33 acts through the sun gear 58, the planet gears 60, and the internal gear 61 to drive the paying-out drum 51 in the opposite direction from the shaft 33, and at a slower speed, thus permitting the cable 73 to be paid out as the mining machine moves along toward the dead man 89. The forward pull on the mining machine by the cable 72 is at the front inner corner of the frame, where the

pulley 80 is mounted, and the backward pull by the cable 73 is at the rear outer corner of the frame, where the pulley 78 is mounted, so that by the reaction of the two cables the cutter chain may be advanced through the coal toward the dead man 89. The speed at which the cable 73 is paid out may be varied by changing the setting of the handle 65, to allow more or less slipping of the brake wheel 63. By making this paying-out of the cable 73 slower than the winding up of the cable 72, which can be done by properly adjusting the handle 65, the mining machine may be given a fan-like movement, with the projecting end of the arm 16 advancing more rapidly than does the frame 15. This fan-like movement is found in practice to be very advantageous. The extent of the turning to produce this fan-like movement is controlled by the handle 65, and the feed of forward movement is controlled by the handle 49. The pull of the cable 73 on the paying-out drum 51 under these conditions tends to move such drum in the same direction as the shaft 33 tends to move it so that the pull of the cable 73 acts through the drum 51 and its connected part on the shaft 33 to aid in driving such shaft, thus economizing in energy by relieving the motor 25 from part of the pull of the cable 72. By releasing the brake band 64, the outer end of the frame 15 may be made to advance more rapidly, thus lengthening the radius of the fan-like movement, or even causing the turning to be in the outer direction; so that by alternately tightening and loosening such brake band, a series of the fan-like movements may be obtained. In fact, by adjustment of such brake band the character of the movement may be made practically anything desired. The paying-out operation of the cable 73 from the drum 51 may be controlled by either the clutch 68 or the brake band 64, with the cable 73 wound in either direction on the drum 51 in either case. If the cable is wound in the direction shown, the use of the brake band 64 to control the paying-out operation makes the pull of the cable 73 assist the motor 25 to drive the shaft 33, while the use of the clutch 68 to control such paying-out operation makes the pull of such cable an additional load on the motor. If the cable is wound in the opposite direction the reverse is the case, the use of the brake band 64 to control the paying-out operation making the pull of such cable an additional load on the motor, and the use of the clutch 68 to control such paying-out operation making the pull of the cable 73 assist the motor 25 to drive the shaft 33.

It will be understood during all the various operations described that where a chain or single continuous flexible feeding mem-

ber is employed instead of two separate ropes, the only point that must be observed is the necessity of providing an adequate loop in the chain between the point at which it leaves the feed operating member 50 and 70 winds on to the feed operating member 51. An inspection of Figs. 12, 13 and 14 will illustrate this feature. In Fig. 12 there is seen a machine shown diagrammatically with the bar perpendicular to the face and cutting across the face and it will be noted that there is a substantial bight 76 in the chain between the feed operating and take-up members; otherwise put, there is a substantial slack in the portion of the chain 80 which lies between the point at which the chain leaves the machine frame at the opposite ends thereof. In Fig. 13 the machine is shown with the cutter bar in advance of the rear end of the machine by quite a substantial amount, a somewhat extreme case being shown for clarity of illustration. Here it will be noted that more chain has been taken in by the feed operating member 50 than has been paid out by the take-up member 51 so that the loose chain in the bight has been increased, thereby increasing the length of the portion of the chain between the points at which the chain leaves the machine frame at its opposite ends. Of course 90 it will be understood that a corresponding position of the machine relative to the working face may be secured in various other ways, for example, by releasing the drum 50 by means of the handle 56 and connecting the drum 51 directly to the shaft 33 and pulling the rear end of the machine around by the drum 51 and the portion 75 of the chain, after which the drum 51 might again be run in its original direction, the operator 100 throwing the handle 56 to cause the drum 50 to become active and so that the machine will move ahead as previously described. Also this position could be secured from a position perpendicular to the face by simply 110 connecting drum 51 directly to shaft 33 while drum 50 still winds in. It may be noted, moreover, that by reason of the fact that the member 51 tends to pay out the portion 75 more slowly than the portion 74 115 is wound in by the member 50, a position corresponding to that shown in Fig. 13 would be reached automatically unless the friction band 64 were allowed to slip. Fig. 14 shows a position of the machine in which 120 the rear end of the machine has been allowed to get ahead of the cutter bar, this being accomplished, for example, by slackening up on the brake band 64 so that the portion 75 of the chain is paid out more rapidly than the portion 74 is wound in. In this operation of the parts it will be noted that the slack bight has been substantially diminished and that there is less chain between the points at which the feed operating mem- 125

ber leaves the machine at its opposite ends than in either of the other two positions.

In this application I do not specifically claim the continuous feed operating form of mechanism shown in Fig. 7, the same instead forming the subject matter of my copending divisional application, Ser. No. 722,372, filed June 25, 1924, nor do I claim the combination of the two species shown herein whereby with the same body of the machine, a machine of either the continuous feed member type or of the two separate feed member type, may be produced when desired, this forming the subject matter of my copending divisional application, Ser. No. 744,521, filed Oct. 18, 1924.

I do not herein claim certain of the broader phases of the feed so broadly as to include the inventions of one Morris P. Holmes covered by his applications Serial No. 555, 20 916, filed Nov. 10, 1916, and Serial No. 224, 072, filed Mar. 22, 1918, which though filed after the present application antedate the same and the divisions of the present application, Serial Nos. 722,372 and 744,521, as to the features referred to.

While I have in this application specifically described different embodiments which my invention may assume in practice, it will be understood that these forms of the same have been described for illustrative purposes and that my invention may be modified and embodied in various other forms without departing from its spirit or the scope of the appended claims.

I claim as my invention:

1. The combination with a mining machine, of feeding mechanism therefor comprising a driving motor, a shaft, a variable speed connection between said motor and said shaft, two drums driven from said shaft, and a variable speed connection between said shaft and one of said drums.

2. The combination with a mining machine, of feeding mechanism therefor comprising a driving motor, a shaft, a variable speed connection between said motor and said shaft, two drums driven from said shaft, a variable speed connection between said shaft and one of said drums, and means for connecting and disconnecting the other of said drums and the shaft.

3. The combination with a mining machine, of feeding mechanism therefor comprising a driving motor, a shaft, a variable speed connection between said motor and said shaft, two drums driven from said shaft, and a reversible and speed-varying connection between said shaft and one of said drums.

4. The combination with a mining machine, of feeding mechanism therefor comprising a driving motor, a shaft, a variable speed connection between said motor and said shaft, two drums driven from said

shaft, and a reversible connection between said shaft and one of said drums.

5. The combination with a mining machine, of feeding mechanism therefor comprising a driving motor, a shaft, a variable speed connection between said motor and said shaft, two drums driven from said shaft, a reversible and speed-varying connection between said shaft and one of said drums, and means for connecting and disconnecting the other of said drums and the shaft.

6. The combination with a mining machine, of feeding mechanism therefor comprising a driving motor, a shaft, a variable speed connection between said motor and said shaft, two drums driven from said shaft, a reversible connection between said shaft and one of said drums, and means for connecting and disconnecting the other of said drums and the shaft.

7. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, and a variable speed connection between said shaft and one of said drums.

8. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, a variable speed connection between said shaft and one of said drums, and means for connecting and disconnecting the other of said drums and the shaft.

9. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, and a reversible and speed-varying connection between said shaft and one of said drums.

10. The combination with a mining machine, of feeding mechanism therefor comprising a driving motor, a shaft, a connection between said motor and said shaft for driving the latter at either high or low speed, two drums driven from said shaft, and a reversible connection between said shaft and one of said drums.

11. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, a reversible and speed-varying connection between said shaft and one of said drums, and means for connecting and disconnecting the other of said drums and the shaft. 70
15. 12. The combination with a mining machine, of feeding mechanism therefor comprising a driving motor, a shaft, a connection between said motor and said shaft for driving the latter at either high or low speed, two drums driven from said shaft, a reversible connection between said shaft and one of said drums, and means for connecting and disconnecting the other of said drums and the shaft. 80
25. 13. The combination with a mining machine, of feeding mechanism therefor comprising a driving shaft, two drums driven from said shaft, a variable speed driving connection for said shaft, and a reversible and speed-varying connection between said shaft and one of said drums. 90
35. 14. The combination with a mining machine, of feeding mechanism therefor comprising a driving shaft, two drums driven from said shaft, a variable speed driving connection for said shaft, and a reversible connection between said shaft and one of said drums. 100
45. 15. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, and a connection between said shaft and one of said drums for producing high forward and low backward speeds of said drum, said last-named connection for high speed drive including a friction device which may be adjusted to produce variations in the speed of such drive. 110
50. 55. 16. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, and a connection between said shaft and one of said drums for producing high and low speeds of said drum, said last-named connection for low speed drive including a friction device which may be adjusted to produce variations in the speed of such drive. 115
60. 65. 20. The combination with a mining machine, of feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, and a connection between said shaft and one of said drums for producing high and low speeds of said drum, said last- 120
70. 75. 80. 85. 90. 95. 100. 105. 110. 115. 120. 125. 130.

named connection for both speed drives including a friction device which may be adjusted to produce variations in the speed of such drive.

- 5 21. In a mining machine, a frame, cutting mechanism carried thereby, a winding drum, a tension member operated by said winding drum and extending forward from said frame near the end toward the cutter, 10 a paying-out drum, a tension member operated by said paying-out drum and extending backward from said frame at a point farther away from the cutter end than is said first tension member, a motor for operating said two drums to feed the frame forward, a member driven by said motor for driving said cutting mechanism, an intermediate power-transmitting member, a connection from said first named member to 15 said intermediate member, said connection including a friction device which may be adjusted to produce varying slipping during feeding, and connections from said intermediate member to both said drums, the connection to one of said drums including a friction device which may be adjusted to produce varying slipping.

22. The combination with a mining machine, a feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, a variable speed connection between said shaft and one of said drums, and a reversible connection between said shaft 40 and one of said drums.

23. The combination with a mining machine, a feeding mechanism therefor comprising a driving motor, a shaft, a connection between said motor and said shaft for driving the latter at either high or low speed, the low speed drive including a friction device which may be adjusted for varying slipping to produce variations in the slow speed drive, two drums driven from said shaft, a variable speed connection between said shaft and one of said drums, a reversible connection between said shaft and one of said drums, and means for connecting and disconnecting the other of said drums and the shaft.

24. In a mining machine, a frame having a forwardly projecting cutter bar, feeding mechanism including a rotating member rotatable on a transverse axis and disposed 60 at one side of said machine at the rear thereof and a cooperating winding member likewise disposed on a transverse axis at the opposite side of the machine and at the rear thereof, and means adjustable at will 65 to rotate said rotating member and winding

member in either the same or opposite directions.

25. In a mining machine, a frame having a forwardly projecting cutter bar, feeding mechanism including a rotating member 70 rotatable on a transverse axis and disposed at one side of said machine at the rear thereof and a cooperating winding member likewise disposed on a transverse axis at the opposite side of the machine and at the 75 rear thereof, and friction controlled means adjustable to control the direction of rotation of said winding member.

26. In a mining machine, a frame having a forwardly projecting cutter bar, feeding mechanism thereon including flexible feeding portions acting on the opposite ends of said frame, a feeding member rotatable on a transverse axis and disposed at one side of said frame, a cooperating take-up 80 member likewise disposed on a transverse axis at the opposite side of said frame, and power driven means for rotating said members having provision for rotating said take-up member to wind in at a plurality of 85 predetermined speeds.

27. In a mining machine, a frame having a forwardly projecting cutter bar, feeding mechanism thereon including flexible feeding portions acting on the opposite ends of 90 said frame, a feeding member rotatable on a transverse axis and disposed at one side of said frame, a cooperating take-up member likewise disposed on a transverse axis 100 at the opposite side of said frame, and power driven means for rotating each of said members having provision for rotating each of said members to wind in at a plurality of predetermined speeds.

28. In a mining machine, a frame having a forwardly projecting cutter bar, feeding mechanism thereon including a feeding member rotatable on a transverse axis and disposed at one side of said frame and a cooperating feeding member likewise disposed on a transverse axis at the opposite side of said frame, power driven means for 105 rotating each of said members at a plurality of speeds independently of the other, and a frictional brake member for controlling 110 the rotation of each of said members.

29. In a mining machine, a frame having a forwardly projecting cutter bar, a motor on the front end of said frame, a feeding member disposed on a transverse axis 115 at one side of said frame and a cooperating feeding member disposed on a transverse axis at the opposite side of said frame, and operative connections between said members and said motor including transmission 120 mechanism and independently operable brake members controlling the rotation of said members.

30. In a mining machine, a frame having a forwardly projecting cutter bar and a cut- 130

- ter chain movable on the latter, a motor on the front end of said frame operatively connected to said cutter chain, a transverse feed shaft operatively connected to said motor 5 and disposed in rear thereof, a feeding member disposed on a transverse axis at one side of said frame and driven by said shaft, a cooperating feeding member disposed on a transverse axis at the opposite side of said frame and driven by said shaft, a clutch controlling the rotation of each of said members, and independently operable brake members controlling said members.
31. In a mining machine, a frame having 15 a forwardly projecting cutter bar and a cutter chain movable on the latter, a motor on the front end of said frame operatively connected to said cutter chain, a transverse feed shaft operatively connected to said motor 20 and disposed in rear thereof, a feeding member disposed on a transverse axis at one side of said frame and driven by said shaft, a cooperating feeding member disposed on a transverse axis at the opposite side of said frame and driven by said shaft, a clutch controlling the rotation of each of said members and located between the same, and brake members disposed on opposite sides of said clutch and controlling said feeding 30 members.
32. A mining machine including a frame 35 disposable laterally in opposite directions from opposite ends of said frame, feed operating and take-up members acting respectively on the advance and receding portions and rotatable on parallel axes and disposed adjacent opposite sides of said frame to the rear of the front end of said motor, and means operative to effect rotation of said feed operating and take-up 40 members to wind in the advance and lengthen the receding portions and having provision for rotating each of said members by power and without reversing the motor to wind in its associated flexible portion at a plurality of predetermined speeds including a predetermined speed during cutting.
33. A mining machine including a frame 45 disposable laterally in opposite directions from opposite ends of the frame, feed operating and take-up members acting respectively on the advance and receding portions, and means operative to wind in the former portion and lengthen the latter having provision effective without reversal of the motor 50 to cause rotation of said members by power in opposite directions to each other and each at a plurality of predetermined speeds including a predetermined speed during cutting, and a predetermined speed in excess of the maximum potential cutting speed of 70 said machine under normal working conditions.
34. A mining machine including a frame 75 disposable on a mine bottom and having cutting mechanism projecting therefrom, and flexible feeding means including a plurality of flexible feeding portions having free extremities, feed operating and take-up members cooperating with said portions, a motor so disposed that its forward end is in advance of said feed operating and take-up members, and feed operating and controlling mechanism operatively connected to said motor and including a frictional controlling device, said mechanism having provision for 80 causing said feed operating and take-up members to wind in simultaneously by power both of said portions at predetermined cutting speeds during cutting and also having provision for effecting winding in one portion 85 while lengthening the other.
35. A mining machine including a frame 90 disposable on a mine bottom and having cutting mechanism projecting therefrom, and flexible feeding means including a plurality of flexible feeding portions having free extremities, feed operating and take-up members cooperating with said portions and rotating on transverse axes, a motor on said frame forward of said axes, and feed-operating and controlling mechanism operatively connected to said motor and including a frictional controlling device, said mechanism having provision for causing said feed operating and take-up members to wind 95 in simultaneously by power both of said portions at predetermined cutting speeds during cutting or either of said portions at a cutting speed and also having provision for effecting winding in one portion while 100 lengthening the other.
36. The combination with a mining machine including a frame disposable on a mine bottom and cutting mechanism projecting therefrom, of flexible feeding means having a plurality of flexible feeding portions having free extremities, feed operating and take-up members cooperating with said portions, a motor on said frame disposed in a position thereon wherein its forward side 105 is nearer the front end of said frame than said feed operating and take-up members, and operating and controlling mechanism operatively connected to said motor and including a frictional controlling device, said mechanism having provision for winding in either of said members by power at a predetermined speed and at a higher speed and having provision for winding in one at a cutting speed while lengthening the other.

37. The combination with a mining machine including a frame slideable on a mine bottom and cutter mechanism projecting therefrom, of flexible feeding means having a plurality of flexible feeding portions having free extremities, feed operating and take-up members cooperating with said portions, a motor on said frame disposed in a position thereon wherein its forward side 10 is nearer the front end of said frame than said feed operating and take-up members, and operating and controlling mechanism operatively connected to said motor and including a frictional controlling device, said 15 mechanism having provision for winding in either or both of said members by power at a predetermined speed and at a higher speed and having provision for winding in one at a cutting speed while lengthening the 20 other, all without changing the mode of operative connection between said members and portions or reversing said motor.

38. In a mining machine, feeding mechanism including a flexible feeding portion, 25 a transmission shaft, a winding member on said transmission shaft adapted to cooperate directly with said flexible feeding portion, and means for operatively connecting said member to said shaft for rotation in the 30 same direction with the latter or oppositely thereto.

39. In a mining machine, feeding mechanism including a transmission shaft, a transmission member thereon, and means 35 for yieldingly connecting said member and shaft for rotation in the same or opposite directions.

40. In a mining machine, feeding mechanism including a transmission shaft, a transmission member thereon, and a plurality of friction devices for respectively connecting said member and shaft for rotation in the same or opposite directions.

41. In a mining machine, feeding mechanism including a transmission shaft, a transmission member thereon, means for operatively connecting said member and shaft for rotation in the same or opposite directions, and supplementary speed changing 50 mechanism cooperating therewith.

42. A mining machine slideable on its bottom over a mine bottom during cutting comprising a driving motor, a cutter bar, operative driving connections between said motor and said bar, and feeding mechanism including a shaft, a variable speed connection between said motor and said shaft including a plurality of cooperating gears one of which is a friction controlled reaction gear and adapted to be held stationary or released to different extents, two drums each adapted to be driven by said shaft, and flexible feeding portions cooperating respectively one with each of said drums.

43. A mining machine slideable on its bot-

tom over a mine bottom during cutting comprising a driving motor, a cutter bar, operative connections between said motor and said bar, and feeding mechanism including a shaft, multi-speed driving connections between said motor and said shaft whereby the former may drive the latter at a plurality of predetermined speeds, said connections including at one of said predetermined speeds a friction controlled reaction gear and an orbitally moving gear cooperating therewith, two drums each adapted to be driven by said shaft, and flexible feeding portions cooperating respectively one with each of said drums.

44. A mining machine slideable on its bottom over a mine bottom during cutting comprising a driving motor, a cutter bar, operative connections between said motor and said bar, and feeding mechanism including a transversely extending shaft, multi-speed driving connections between said motor and said shaft whereby the former may drive the latter at a plurality of predetermined speeds, two drums each adapted to be driven by said shaft in a manner to wind in a flexible feeding portion cooperating therewith, and each rotating on a transversely extending axis, and flexible feeding portions cooperating respectively one with each of said drums.

45. A mining machine slideable on its bottom over a mine bottom during cutting comprising a driving motor, a cutter bar, operative connections between said motor and said bar, and feeding mechanism including a transversely extending shaft, multi-speed driving connections between said motor and said shaft whereby the former may drive the latter at a plurality of predetermined speeds, two drums each adapted to be driven by said shaft, means under manual control for operatively connecting either of said drums in driving relation to said shaft, and flexible feeding portions cooperating respectively one with each of said drums.

46. A mining machine slideable on its bottom over a mine bottom during cutting comprising a driving motor, a cutter bar, operative driving connections between said motor and bar, and feeding mechanism including a shaft, means actuated by said motor for driving said shaft at a plurality of predetermined speeds, two drums each adapted to be driven by said shaft, one of said drums constituting a feed operating drum and the other a paying-out drum during cutting across a face, means for connecting and disconnecting said feed operating drum with said shaft, friction controlled means for retarding the rotation of said paying-out drum, and flexible feeding portions cooperating respectively one with each of said drums.

47. A mining machine slideable on its bottom over a mine bottom during cutting comprising a driving motor, a cutter bar, operative driving connections between said 5 motor and bar, and feeding mechanism including a shaft, means actuated by said motor for driving said shaft at a plurality of predetermined speeds including at the slower of said speeds a friction controlled 10 reaction member, two drums each adapted to be driven by said shaft, one of said drums constituting a feed operating drum and the other a paying-out drum during cutting across a face, means for connecting and dis- 15 connecting said feed operating drum with said shaft, friction controlled means for retarding the rotation of said paying-out drum, and flexible feeding portions cooper- 20 ating respectively one with each of said drums.

48. The combination with a mining machine, of feeding mechanism therefor comprising a driving motor, a shaft, a plural speed connection between said motor and 25 said shaft whereby the latter may be driven at a plurality of predetermined speeds by the former, two drums operatively connectible with said shaft, and means for connecting one of said drums to said shaft for dry- 30 ing thereby at a plurality of predetermined speeds while rotation of said shaft remains constant.

49. The combination with a mining machine, of feeding mechanism therefor comprising a driving motor, a shaft, a plural speed connection between said motor and said shaft whereby the latter may be driven at a plurality of predetermined speeds by the former, two drums operatively connectible with said shaft, and means for connecting one of said drums to said shaft for driving thereby at a predetermined speed in one direction and at a different predetermined speed in the opposite direction while 45 the rotation of said shaft remains constant.

50. The combination with a mining machine, of feeding mechanism therefor comprising a driving motor, a shaft, a plural speed connection between said motor and 50 said shaft whereby the latter may be driven at a plurality of predetermined speeds by the former, two drums operatively connectible with said shaft, and means for connecting one of said drums to said shaft for driving thereby at a predetermined speed in one direction and at a different predetermined speed in the opposite direction while the rotation of said shaft remains constant, the angular rate of one of said predetermined speeds being equal to the angular 55 rate of rotation of said shaft.

51. The combination with a mining machine, of feeding mechanism therefor comprising a driving motor, a shaft, a plural speed connection between said motor and 60

said shaft whereby the latter may be driven at a plurality of predetermined speeds by the former, two drums operatively connectible with said shaft, and means for connecting one of said drums to said shaft for 70 driving thereby at a plurality of predetermined speeds while rotation of said shaft remains constant, said means for connecting said drum to said shaft including friction mechanism controllable to vary the rotation of said drum from said predetermined speeds.

52. The combination with a mining machine, of feeding mechanism therefor comprising a driving motor, a shaft, a plural speed connection between said motor and said shaft whereby the latter may be driven at a plurality of predetermined speeds by the former, two drums operatively connectible with said shaft, and means for connecting one of said drums to said shaft for 80 driving thereby at a predetermined speed in one direction and at a different predetermined speed in the opposite direction while the rotation of said shaft remains constant, 90 said means for connecting said drum to said shaft including friction mechanism controllable to vary the rotation of said drum from said predetermined speeds.

53. The combination with a mining machine, of feeding mechanism therefor comprising a driving motor, a shaft, a plural speed connection between said motor and said shaft whereby the latter may be driven at a plurality of predetermined speeds by the former, two drums operatively connectible with said shaft, and means for connecting one of said drums to said shaft for driving thereby at a predetermined speed in one direction and at a different predetermined speed in the opposite direction while the rotation of said shaft remains constant, the angular rate of one of said predetermined speeds being equal to the angular rate of rotation of said shaft, said means for connecting said drum to said shaft including friction mechanism controllable to vary the rotation of said drum from said predetermined speeds.

54. The combination with a mining machine, of feeding mechanism therefor comprising a driving motor, a shaft, a plural speed connection between said motor and said shaft whereby the latter may be driven at a plurality of predetermined speeds by the former, said connection including friction mechanism adjustable to variably diminish the speed of said shaft from one of said predetermined speeds, two drums operatively connectible with said shaft, and means for connecting one of said drums to said shaft for driving thereby at a plurality of predetermined speeds while rotation of said shaft remains constant.

55. The combination with a mining ma-

chine of feeding mechanism therefor comprising a driving motor, a shaft, a plural speed connection between said motor and said shaft whereby the latter may be driven at a plurality of predetermined speeds by the former, said connection including friction mechanism adjustable to variably diminish the speed of said shaft from one of said predetermined speeds, two drums operatively connectible with said shaft, and means for connecting one of said drums to said shaft for driving thereby at a predetermined speed in one direction and at a different predetermined speed in the opposite direction while the rotation of said shaft remains constant.

56. The combination with a mining machine, of feeding mechanism therefor comprising a driving motor, a shaft, a plural speed connection between said motor and said shaft whereby the latter may be driven at a plurality of predetermined speeds by the former, said connection including friction mechanism adjustable to variably diminish the speed of said shaft from one of said predetermined speeds, two drums operatively connectible with said shaft, and means for connecting one of said drums to said shaft for driving thereby at a predetermined speed in one direction and at a different predetermined speed in the opposite direction while the rotation of said shaft remains constant, the angular rate of one of said predetermined speeds being equal to the angular rate of rotation of said shaft.

57. The combination with a mining machine, of feeding mechanism therefor comprising a driving motor, a shaft, a plural speed connection between said motor and said shaft whereby the latter may be driven at a plurality of predetermined speeds by the former, said connection including friction mechanism adjustable to variably diminish the speed of said shaft from one of said predetermined speeds, two drums operatively connectible with said shaft, and means for connecting one of said drums to said shaft for driving thereby at a plurality of predetermined speeds while rotation of said shaft remains constant, said means for connecting said drum to said shaft including friction mechanism controllable to vary the rotation of said drum from one of said predetermined speeds.

58. The combination with a mining machine, of feeding mechanism therefor comprising a driving motor, a shaft, a plural speed connection between said motor and said shaft whereby the latter may be driven at a plurality of predetermined speeds by the former, said connection including friction mechanism adjustable to variably diminish the speed of said shaft from one of said predetermined speeds, two drums opera-

tively connectible with said shaft, and means for connecting one of said drums to said shaft for driving thereby at a predetermined speed in one direction and at a different predetermined speed in the opposite direction while the rotation of said shaft remains constant, said means for connecting said drum to said shaft including friction mechanism controllable to vary the rotation of said drum from one of said predetermined speeds.

59. The combination with a mining machine, of feeding mechanism therefor comprising a driving motor, a shaft, a plural speed connection between said motor and said shaft whereby the latter may be driven at a plurality of predetermined speeds by the former, said connection including friction mechanism adjustable to variably diminish the speed of said shaft from one of said predetermined speeds, two drums operatively connectible with said shaft, and means for connecting one of said drums to said shaft for driving thereby at a predetermined speed in one direction and at a different predetermined speed in the opposite direction while the rotation of said shaft remains constant, the angular rate of one of said predetermined speeds being equal to the angular rate of rotation of said shaft, said means for connecting said drum to said shaft including friction mechanism controllable to vary the rotation of said drum from one of said predetermined speeds.

60. The combination with a mining machine, of feeding mechanism therefor comprising a driving motor, a shaft, a plural speed connection between said motor and said shaft whereby the latter may be driven at a plurality of predetermined speeds by the former, two drums operatively connectible with said shaft, and means for connecting one of said drums to said shaft for driving thereby at a plurality of predetermined speeds while rotation of said shaft remains constant, said means for connecting said drum to said shaft including friction mechanism controllable to vary the rotation of said drum from one of said predetermined speeds.

61. The combination with a mining machine, of feeding mechanism therefor comprising a driving motor, a shaft, a plural speed connection between said motor and said shaft whereby the latter may be driven at a plurality of predetermined speeds by the former, two drums operatively connectible with said shaft, and means for connecting one of said drums to said shaft for driving thereby at a predetermined speed in one direction and at a different predetermined speed in the opposite direction while the rotation of said shaft remains constant, said means for connecting said drum to said shaft

including friction mechanism controllable to vary the rotation of said drum from one of said predetermined speeds.

62. The combination with a mining machine, of feeding mechanism therefor comprising a driving motor, a shaft, a plural speed connection between said motor and said shaft whereby the latter may be driven at a plurality of predetermined speeds by the former, two drums operatively connectible with said shaft, and means for connecting one of said drums to said shaft for driving thereby at a predetermined speed in one direction and at a different predetermined speed in the opposite direction while the rotation of said shaft remains constant, the angular rate of one of said predetermined speeds being equal to the angular rate of rotation of said shaft, said means for connecting said drum to said shaft including friction mechanism controllable to vary the rotation of said drum from one of said predetermined speeds.

63. In a mining machine, a frame having a forwardly projecting cutter bar, a motor on said frame, a feed operating member rotatable on a transverse axis at one side of said frame, a flexible feeding member co-operating therewith, operative connections between said feed operating member and said motor including intermeshing elements respectively coaxial with said feed operating member and fixed as to relative rotary movement with respect thereto, and constituting a driving member for said last mentioned element, and means for supporting said feed operating member permitting interruption of said drive including a laterally projecting shaft, an eccentric sleeve rotatably mounted thereon and providing a bearing for said feed operating member whose axis is offset from the axis of said laterally projecting shaft, and means for rotating said eccentric sleeve to bring said first mentioned element into mesh with said second mentioned element and to move it out of mesh.

64. In a mining machine, a frame having a forwardly projecting cutter bar, a motor on said frame, a feed operating member rotatable on a transverse axis at one side of said frame, a flexible feeding member co-operating therewith, operative connections between said feed operating member and said motor including intermeshing elements respectively coaxial with said feed operating member and fixed as to relative rotary movement with respect thereto, and constituting a driving member for said last mentioned element, and means for supporting said feed operating member permitting interruption of said drive including a laterally projecting shaft, an eccentric sleeve rotatably mounted thereon and providing a bearing for said feed operating member whose axis

is offset from the axis of said laterally projecting shaft, and means for rotating said eccentric sleeve to bring said first mentioned element into mesh with said second mentioned element and to move it out of mesh arranged at the opposite side of said feed operating member with respect to the longitudinal center line of the machine frame and including an element manually movable to move the eccentric sleeve, and means providing a plurality of stationary abutments at appropriate places.

65. In a mining machine, the combination with a main frame adapted to rest upon and slide over the floor of a mine, a motor carried by the main frame, an endless chain cutting mechanism projecting horizontally from the main frame, a winding drum mounted on the main frame, a rope windable thereon, a train of gearing operative to connect the drum and the motor to cause the drum to wind in the rope at a relatively low speed, mechanism operative to break the train of gearing adjacent the drum to allow the free unwinding of the rope, a second winding drum mounted upon the main frame, a rope windable thereon, a gear train including a friction clutch adapted to connect the second mentioned drum with the motor to wind the second mentioned rope at a relatively higher speed, and means for interrupting the driving connection between said drum and said motor.

66. The combination with a mining machine including a frame slidable on a mine bottom and a projecting cutter bar, of means for feeding said frame laterally during cutting including a plurality of flexible feeding portions disposable in opposite directions from the opposite ends thereof, and feed operating and controlling means including a motor and a plurality of elements disposed to the rear of the front end of said motor and simultaneously rotatable by power transmitted directly thereto from the latter respectively to wind in the advancing portion and to pay out the receding portion, said feed operating and controlling means also including means for rotating said paying out element to wind in said receding portion at a predetermined speed in excess of the speed at which said advance portion is wound in whereby said bar may be sumped into the coal.

67. The combination with a mining machine including a frame slidable on a mine bottom and a projecting cutter bar, of means for feeding said frame laterally during cutting including a plurality of flexible feeding members disposable in opposite directions from the opposite ends thereof, and feed operating and controlling means including a motor and a plurality of elements arranged to the rear of the front of said

motor and simultaneously rotatable by power from said motor respectively to wind in the advancing portion and pay out the receding portion, said feed operating and controlling means also including means for rotating said paying out element to wind in said receding portion at a predetermined speed in excess of the speed at which said advance portion is wound in while said 5 advance portion is wound in while said 10 winding in element is stationary as regards rotation.

68. The combination with a mining machine including a frame slideable on a mine bottom and a projecting cutter bar, of means 15 for feeding said frame laterally during cutting including a plurality of flexible feeding members disposable in opposite directions from the opposite ends thereof, and feed operating and controlling means including a plurality of elements arranged 20 at opposite sides of said frame and substantially opposite each other and simultaneously rotatable by power respectively to wind in the advancing portion and pay out the receding portion, said feed operating 25 and controlling means also including means for rotating said paying out element to wind in said receding portion at a predetermined speed in excess of the speed at which said 30 advance portion is wound in while said winding in element is either winding in or stationary as regards rotation.

69. A room and pillar mining machine including a motor having its armature shaft 35 rotatable on an axis extending longitudinally of the machine, a bevel driving pinion upon the rear end of said shaft, a bevel gear rotating on a vertical axis to the rear of said armature shaft and disposed above and meshing with said driving pinion, a cutter chain driving sprocket, a driving connection 40 between said bevel gear and said driving sprocket, and mechanism for feeding said machine over the mine bottom and guiding the same during its feeding movement bodily laterally along a mine face including a plurality of flexible feeding portions 45 extending in opposite directions from the opposite ends of the machine frame and constituting during transverse feeding advance and receding portions, a worm coaxial with and rotated by said bevel gear, a transverse shaft carrying a worm wheel driven by said 50 worm, a feed operating member cooperating with said advance portion and rotating on a transversely extending axis offset from said transverse shaft, a member rotating coaxially with said transverse shaft and cooperating with said receding portion, and means for frictionally controlling the rotation of said members including friction mechanism coaxial with said transverse 55 shaft.

70. A room and pillar mining machine including a motor having its armature shaft rotatable on an axis extending longitudinally of the machine, a bevel driving pinion 60 upon the rear end of said shaft, a bevel

gear rotating on a vertical axis to the rear of said armature shaft and disposed above and meshing with said driving pinion, a cutter chain driving sprocket, a driving connection between said bevel gear and said driving sprocket, and mechanism for feeding said machine over the mine bottom and guiding the same during its feeding movement bodily laterally along the mine face including a plurality of flexible feeding portions 70 extending in opposite directions from the opposite ends of the machine frame and constituting during transverse feeding advance and receding portions, a worm coaxial with and rotated by said bevel gear, a transverse shaft carrying a worm wheel driven by said worm, a feed operating member cooperating with said advance portion and rotating on a transversely extending axis offset from said transverse shaft, a member rotating coaxially with said transverse shaft and cooperating with said receding portion, and means for frictionally controlling the rotation of said members 75 during cutting.

71. A room and pillar mining machine including a motor having its armature shaft rotatable on an axis extending longitudinally of the machine, a bevel driving pinion upon the rear end of said shaft, a bevel gear rotating on a vertical axis to the rear of said armature shaft and disposed above and meshing with said driving pinion, a cutter chain driving sprocket, a driving connection 80 between said bevel gear and said driving sprocket, and mechanism for feeding said machine over the mine bottom and guiding the same during its feeding movement bodily laterally along a mine face including a plurality of flexible feeding portions 85 extending in opposite directions from the opposite ends of the machine frame and constituting during transverse feeding advance and receding portions, a worm coaxial with and rotated by said bevel gear, a transverse shaft carrying a worm wheel driven by said worm, a feed operating member cooperating with said advance portion and rotating on a transversely extending axis offset from said transverse shaft, a member rotating coaxially with said transverse shaft and cooperating with said receding portion, and means for frictionally controlling the rotation of said members 90 during cutting.

72. A room and pillar mining machine including a motor having its armature shaft rotatable on an axis extending longitudinally of the machine, a bevel driving pinion upon the rear end of said shaft, a bevel gear rotating on a vertical axis to the rear of said armature shaft and disposed above and meshing with said driving pinion, a cutter chain driving sprocket, a driving connection 95 between said bevel gear and said driving sprocket, and mechanism for feeding said machine over the mine bottom and guiding the same during its feeding movement bodily laterally along a mine face including a plurality of flexible feeding portions 100 extending in opposite directions from the opposite ends of the machine frame and constituting during transverse feeding advance and receding portions, a worm coaxial with and rotated by said bevel gear, a transverse shaft carrying a worm wheel driven by said worm, a feed operating member cooperating with said advance portion and rotating on a transversely extending axis offset from said transverse shaft, a member rotating coaxially with said transverse shaft and cooperating with said receding portion, and means for frictionally controlling the rotation of said members 105 during cutting.

73. A room and pillar mining machine including a motor having its armature shaft rotatable on an axis extending longitudinally of the machine, a bevel driving pinion upon the rear end of said shaft, a bevel gear rotating on a vertical axis to the rear of said armature shaft and disposed above and meshing with said driving pinion, a cutter chain driving sprocket, a driving connection 110 between said bevel gear and said driving sprocket, and mechanism for feeding said machine over the mine bottom and guiding the same during its feeding movement bodily laterally along a mine face including a plurality of flexible feeding portions 115 extending in opposite directions from the opposite ends of the machine frame and constituting during transverse feeding advance and receding portions, a worm coaxial with and rotated by said bevel gear, a transverse shaft carrying a worm wheel driven by said worm, a feed operating member cooperating with said advance portion and rotating on a transversely extending axis offset from said transverse shaft, a member rotating coaxially with said transverse shaft and cooperating with said receding portion, and means for frictionally controlling the rotation of said members 120 during cutting.

between said bevel gear and said driving sprocket, and mechanism for feeding said machine over the mine bottom and guiding the same during its feeding movement bodily laterally along the mine face including a plurality of flexible feeding portions extending in opposite directions from the opposite ends of the machine frame and constituting during transverse feeding advance 10 and receding portions, a worm coaxial with and rotated by said bevel gear, a transverse shaft carrying a worm wheel driven by said worm, a feed operating member cooperating with said advance portion and rotating on a 15 transversely extending axis offset from said transverse shaft, a member rotating coaxially with said transverse shaft and cooperating with said receding portion, and means for frictionally controlling the operation of 20 said second mentioned member including a friction clutch coaxial therewith.

73. In a mining machine, a machine frame, flexible feeding means therefor including advance and receding flexible feeding portions, feed operating means including a feed operating member adapted to act on said advance portion, a feed operating member adapted to act on said receding portion, a motor on said frame, and variable speed driving connections driven by said motor and operable to rotate said feed operating members including a differential gearing selectively operable to drive either of said feed operating members.

74. In a mining machine, a machine frame, flexible feeding means therefor including advance and receding flexible feeding portions, feed operating means including a feed operating member adapted to act 35 on said advance portion, a feed operating member adapted to act on said receding portion, a motor on said frame, and variable speed driving connections driven by said motor and operable to rotate said feed operating members including a differential gearing selectively operable to drive either of said feed operating members at different speeds.

75. In a mining machine, a machine frame, flexible feeding means therefor including advance and receding flexible feeding portions, feed operating means including a feed operating member acting on said advance portion, a feed operating member 50 acting on said receding portion, a motor on said frame, and variable speed driving connections driven by said motor and operable to rotate said second mentioned feed operating member including a differential gearing selectively operable to drive said last mentioned feed operating member at different predetermined speeds while disconnected from said first mentioned feed operating member, said predetermined speeds including a speed in excess of the maximum poten-

tial cutting speed of the machine under normal working conditions.

76. In a mining machine, a machine frame, flexible feeding means thereon including advance and receding flexible feeding portions, feed operating means including a feed operating member acting on said receding portion, a motor on said frame, and variable speed driving connections driven by said motor and operable to rotate 75 said feed operating member including an epicyclic gearing whose elements are included in the driving connections during rotation of said feed operating member at each speed thereof and selectively operable to drive said feed operating member at different predetermined speeds to effect winding in of a flexible feeding portion cooperating therewith at different predetermined speeds 80 one of which substantially exceeds the maximum potential cutting speed of said machine under normal working conditions.

77. In a mining machine, a machine frame, flexible feeding means thereon including advance and receding flexible feeding portions, feed operating means including a feed operating member acting on said receding portion, a motor on said frame, and variable speed driving connections frictionally controlled at all speeds and driven by said motor and operable to rotate said feed operating member including an epicyclic gearing whose elements are included in the driving connections during rotation of said feed operating member at each 95 speed thereof and selectively operable to drive said feed operating member at different predetermined speeds the greatest of which is faster than the maximum potential cutting speed under normal conditions.

78. In a mining machine, a machine frame, flexible feeding means therefor including advance and receding flexible feeding portions, feed operating means including a feed operating member adapted to act on said receding portion, a feed operating member adapted to act on said advance portion, a motor on said frame, and variable speed driving connections driven by said motor and operable to rotate said feed operating members including a differential gearing selectively operable to drive either of said feed operating members at different speeds and a friction device disposed in said variable speed driving mechanism.

79. The combination with a mining machine including a frame slidable on a mine bottom and having a rigid longitudinally projecting cutter bar and means for feeding said machine including flexible feeding portions extending from the opposite sides of said frame, and feed operating mechanism including a plurality of winding members one cooperating with each of said flexible feeding portions and operative to draw in 125 130

- either one of said portions separately at a plurality of predetermined speeds one of which is greater than the maximum potential cutting speed under normal conditions, 5 said mechanism also having provision for drawing in one of said portions at a predetermined speed while permitting lengthening of the other at substantially the same speed.
- 10 80. A mining machine slidable on a mine bottom comprising a frame, cutting mechanism thereon including a rotatable cutter chain, a plurality of flexible feeding portions disposable laterally in opposite directions in advance of and receding from the opposite ends of said frame, cutter chain driving means including a motor, and feed operating means driven by said motor including a plurality of rotatable feed operating members one operative to wind in said advance portion while the other pays out said receding portion to effect feed of said machine at a predetermined low speed across a face as said cutter chain is rotated in one direction, said means having provision whereby either of said rotatable members may wind in its associated flexible feeding portion at a plurality of speeds of which one is in excess of the maximum potential cutting speed under normal conditions, all while the motor propels the cutter chain in one direction and with the flexible feeding portions cooperating in the same manner with said feed operating means 35 throughout.
81. A mining machine slidable on a mine bottom comprising a frame, cutting mechanism thereon including a circulating cutter chain, a pair of flexible feeding portions disposable laterally in opposite directions in advance of and receding from the opposite ends of said machine frame, cutter chain driving means, a driving motor therefor, and feed operating means driven by said motor and operative to feed said machine along the receding portion at a cutting speed to effect sumping and thereafter to feed said machine along said advance portion at a substantially equal cutting speed 40 while paying out said receding portion and continuing to drive said cutter chain in the same direction to make a cut across a face, said feed operating means including a plurality of rotatable feed operating members one cooperating with said advance and one with said receding portion, said feed operating members being disposed adjacent opposite sides of said frame and both to the rear of the front of said motor.
- 45 82. A mining machine slidable on a mine bottom comprising a frame, a motor disposed longitudinally thereof, cutting mechanism driven by the rear end of said motor including a cutter chain carrying cutter bar disposed longitudinally of said machine throughout the sumping and lateral cutting operations, and mechanism for sumping said bar into and thereafter feeding it laterally
- throughout the sumping and lateral cutting operations, and mechanism for sumping said bar into and thereafter feeding it laterally across a face including a plurality of flexible feeding portions adapted to form 70 advance and receding portions, means for disposing said receding portion during sumping substantially longitudinally of the receding side of said machine and during lateral cutting disposing said advance portion longitudinally of the advancing side of the machine frame and laterally therefrom and said receding portion reversely laterally from the opposite side of the machine frame, and winding means including winding elements respectively cooperating with said advance and receding portions and driven by the rear end of said motor and operative to effect sumping and lateral feeding, said winding means including connections for effecting the drawing in of either portion at a cutting speed without reversing the cutting mechanism or changing the operative connection between said portions and their cooperating winding elements. 75
83. A mining machine slidable on a mine bottom comprising a frame, a motor disposed longitudinally thereof, cutting mechanism driven by the rear end of said motor including a cutter chain carrying cutter bar disposed longitudinally of said machine throughout the sumping and lateral cutting operations and mechanism for sumping said bar into and thereafter feeding it laterally across a face including a plurality of flexible feeding portions adapted to form advance and receding portions, means for disposing said receding portion during sumping substantially longitudinally of the receding side of said machine and during lateral cutting disposing said advance portion longitudinally of the advancing side of the machine frame and laterally therefrom and said receding portion reversely laterally therefrom, and winding means including winding elements respectively cooperating with said advance and receding portions and driven by the rear end of said motor and operative to effect sumping and lateral feeding, said winding means including connections for effecting the drawing in of either portion at a cutting speed without reversing the cutting mechanism or changing the operative connection between said portions and their cooperating winding elements, or drawing in one portion at a higher speed. 100
84. A mining machine slidable on a mine bottom comprising a frame, a motor disposed longitudinally thereof, cutting mechanism driven by the rear end of said motor including a cutter chain carrying cutter bar disposed longitudinally of said machine throughout the sumping and lateral cutting operations, and mechanism for sumping said bar into and thereafter feeding it laterally

- across a face including a plurality of flexible feeding portions adapted to form advance and receding portions, means for disposing said receding portion during sumping operation substantially longitudinally of the receding side of said machine and during lateral cutting disposing said advance portion longitudinally of the advancing side of the machine frame and laterally therefrom and said receding portion reversely laterally therefrom, and winding means including winding elements respectively cooperating with said advance and receding portions and driven by the rear end of said motor and operative to effect sumping and lateral feeding, said winding means including connections for effecting the drawing in of either portion at a cutting speed without reversing the cutting mechanism or changing the operative connection between said portions and their cooperating winding elements, or drawing in either portion at a higher speed.
85. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally across a face with said cutting mechanism rotating in the same direction as during the cutting operation including a plurality of flexible feeding portions each having a free extremity and one adapted to form the advance and the other the receding portion, means for disposing the advance portion laterally from the advancing side of the machine during lateral cutting and the receding portion substantially along and laterally relative to the receding side thereof during sumping and lateral cutting respectively, and winding means including separate winding members for said portions, said winding means including a fast feed gear train and a slow feed gear train driven by said motor and means for drawing in either portion through either train without reversing the motor or change in operative engagement between said portions and their cooperating winding members.
87. A mining machine slidable relative to a mine bottom comprising a motor, cutting mechanism operatively connected thereto and including a cutter carrying cutter bar disposed longitudinally of said machine throughout the sumping and lateral cutting operations, and means for feeding said bar into and laterally along the face including a plurality of flexible feeding portions each having a free extremity, means for disposing one of said portions substantially longitudinally of the receding side of the machine during sumping and for disposing said portion in opposite directions laterally from the opposite ends of the machine during lateral cutting, winding means cooperating one with each of said portions, and operative transmission connections between said winding means and said motor operative to effect sumping and lateral feeding and to draw in either portion at a speed at which said machine can cut or one portion at a higher speed which is above the maximum potential cutting speed of said machine under normal conditions, all without change in the operative engagement between said winding means and their cooperating flexible feeding portions, said connections including a variable speed gearing and cooperating mechanism for selectively drawing in the desired portion at the desired geared speed.
88. A mining machine slidable relative to a mine bottom comprising a motor, cutting mechanism operatively connected thereto and including a cutter carrying cutter bar disposed longitudinally of said machine throughout the sumping and lateral cutting operations, and means for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine during lateral cutting, winding means for said portions including separate

winding elements individual thereto, and operative transmission connections between said winding means and said motor operative to effect sumping and lateral feeding 5 and to draw in either portion at a speed within the cutting capacity of the machine without reversal of said cutting mechanism or one portion at a higher speed, said connections including variable speed gearing 10 constituting actuating means common to said separate winding elements, adjustable connections for selecting the winding means to be actuated, adjustable connections for selecting the speed, and friction means re- 15 leasable on overload of the cutting means.

89. A mining machine slidable relative to a mine bottom comprising a motor, cutting mechanism operatively connected thereto and including a cutter carrying cutter bar 20 disposed longitudinally of said machine throughout the sumping and lateral cutting operations, and means for feeding said bar into and laterally along a face including a plurality of flexible feeding portions each 25 having a free extremity, means for disposing one portion substantially longitudinally of the receding side of the machine during sumping and both portions in opposite directions laterally from the opposite ends 30 of the machine during lateral cutting, winding means for said portions including separate winding elements individual thereto, and operative transmission connections between said winding means and said motor 35 operative to effect sumping and lateral feeding and to draw in either portion at a speed within the cutting capacity of the machine without reversal of said cutting mechanism or one portion at a higher speed, said connections including variable speed gearing 40 constituting actuating means common to said separate winding elements, adjustable connections for selecting the winding means to be actuated, adjustable connections for 45 selecting the speed, and friction means re- leasable on overload of the cutting speed, said frictional means being controllable to reduce the geared feeds at will.

90. A mining machine slidable relative to 50 a mine bottom comprising a motor, cutting mechanism operatively connected thereto and including a cutter carrying cutter bar disposed longitudinally of said machine throughout the sumping and lateral cutting 55 operations, and means for feeding said bar into and laterally along a face including a plurality of flexible feeding portions each having a free extremity, means for disposing one portion substantially longitudinally 60 of the receding side of the machine during sumping and both portions in opposite directions laterally from the opposite ends of the machine during lateral cutting, winding means for said portions including separate 65 winding elements individual thereto, and

operative transmission connections between the said winding means and said motor operative without reversal of said cutting mechanism to cause said winding means to draw in either portion at different pre- 70 determined speeds and permitting the drawing in of each portion at a predetermined speed within the cutting limits of said machine and at a predetermined higher speed, said higher speed in the case of one of said 75 portions being in excess of the maximum potential cutting speed of the machine under normal working conditions.

91. A mining machine slidable relative to a mine bottom comprising a motor, cutting mechanism operatively connected thereto and including a cutter carrying cutter bar disposed longitudinally of said machine throughout the sumping and lateral cutting operations, and means for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine during lateral cutting, winding means for said portions including separate winding elements individual thereto, and operative transmission connections between the said winding means and said motor operative without reversal of said cutting mechanism or change in operative engagement of said flexible feeding portions to their respective winding elements to cause said winding elements associated therewith to draw in said sumping portion at a pre- 95 determined high speed substantially in excess of the maximum potential cutting speed of said machine under normal working conditions and at a predetermined slower speed or the other portion at a predetermined slow speed while permitting lengthening of said first mentioned portion.

92. A room and pillar mining machine slidable over a mine bottom comprising an electric motor, cutting mechanism driven thereby including a cutter carrying cutter bar and feeding and guiding mechanism for sumping said bar into and thereafter feeding it laterally along a face with said cutting mechanism rotating in the same direction as during the sumping operation, feeding mechanism including advance and receding flexible feeding portions each having a free extremity, guiding means for said portions whereby said machine may be sumped and moved laterally, and winding means for said feeding mechanism driven by said motor, said winding means including a rotatable feed operating element co- 100 operating with one of said flexible feeding portions, a separate rotatable element co- 105 operating with the other thereof, a fast feed 110

- gear train, a slow feed gear train, and means for selectively effecting rotation of either of said elements through either train without reversal of the rotation of the motor.
- 5 93. A room and pillar mining machine slideable on a mine bottom comprising an electric motor, cutting mechanism driven thereby including a cutter carrying cutter bar and feeding and guiding mechanism for 10 sumping said bar into and thereafter feeding it laterally along a face with said cutting mechanism rotating in the same direction as during the sumping operation, feeding mechanism including advance and re- 15 ceding flexible feeding portions each having a free extremity, guiding means for said portions whereby said machine may be sumped and moved laterally, and winding means for said feeding mechanism driven by said motor, said winding means including a rotatable feed operating element co-operating with one of said flexible feeding portions, a separate rotatable element co-operating with the other thereof, a fast feed 20 gear train, a slow feed gear train, and means for selectively effecting rotation of either of said elements through one of said trains and one of said elements through the other of said trains without reversal of the motor.
- 25 94. A room and pillar mining machine slideable on a mine bottom comprising an electric motor, cutting mechanism driven thereby including a cutter carrying cutter bar and feeding and guiding mechanism for 30 sumping said bar into and thereafter feeding it laterally along a face with said cutting mechanism rotating in the same direction as during the sumping operation, feeding mechanism including advance and re- 35 ceding flexible feeding portions each having a free extremity, guiding means for said portions whereby said machine may be sumped and moved laterally, and winding means for said feeding mechanism driven by said motor, said winding means including a rotatable feed operating element co-operating with one of said flexible feeding portions, a separate rotatable element co-operating with the other thereof, a fast feed 40 gear train, a slow feed gear train, and means for selectively effecting rotation of either of said elements through either train without interruption of the rotation of the motor.
- 45 95. A room and pillar mining machine slideable on a mine bottom comprising an electric motor having an armature shaft, cutting mechanism driven by one end of said shaft and including a cutter carrying cutter bar and feeding and guiding mechanism for 50 sumping said bar into and thereafter feeding it laterally along a face with said cutting mechanism rotating in the same direction as during the sumping operation, feeding mechanism including advance and re- 55 ceding flexible feeding portions each having a free extremity, guiding means for said portions whereby said machine may be sumped along one of said portions and then moved laterally between said portion and an advance portion, said winding means including a rotatable feed operating element co-operating with one of said flexible feeding portions, a separate rotatable element co-operating with the other thereof, a fast feed gear train, a slow feed gear train, and means for selectively effecting rotation of either of said elements through either train by power from said motor and without reversal of the latter.
- 60 96. In a mining machine, a machine frame, a horizontal motor rotatable thereon on an axis extending longitudinally of said frame, an upright driving member carried on said frame in rear of said motor, operative connections between said motor and said member comprising mutually meshing members on said motor and member, cutting mechanism including a cutter chain driving sprocket in a plane beneath said motor and operatively connected to said member, a worm on said member, a worm gear rotatable by said worm, flexible feeding mechanism for feeding said frame bodily laterally along the mine face including a feed operating member on said frame, variable speed transmission mechanism between said feed operating member and said worm gear, and a second feed operating member coaxial with an element of said variable speed transmission mechanism.
- 65 97. In a mining machine, a machine frame, a horizontal motor rotatable thereon on an axis extending longitudinally of said frame, an upright driving member carried on said frame in rear of said motor, operative connections between said motor and said member, cutting mechanism including a cutter chain driving sprocket in a plane beneath said motor and operatively connected to said member, a worm on said member, a worm gear rotatable by said worm, flexible feeding mechanism for feeding said frame bodily laterally along the mine face including a feed operating member rotatable on a transverse axis on said frame, a second feed operating member rotatable on a different transverse axis on said frame, and plural-pre-determined speed transmission mechanism between said feed operating members and said worm gear.
- 70 98. In a mining machine, a machine frame, a horizontal motor rotatable thereon on an axis extending longitudinally of said frame, an upright driving member carried on said frame in rear of said motor, operative connections between said motor and said member, cutting mechanism including a cutter chain driving sprocket in a plane beneath said motor and operatively connect-

ed to said member, a worm on said member, a worm gear rotatable by said worm, flexible feeding mechanism for feeding said frame bodily laterally along the mine face including a feed operating member rotatable on a transverse axis on said frame, a second feed operating member rotatable on a different transverse axis on said frame, and common variable speed transmission mechanism between said feed operating members and said worm gear, said second mentioned feed operating member being disposed at the opposite side of said frame from said first mentioned feed operating member and 10 with its axis to the rear of the axis of said first mentioned feed operating member.

99. A room and pillar mining machine 20 slidable upon a mine bottom during cutting and including a machine frame, a motor thereon having its armature shaft rotatable on an axis extending longitudinally of said frame, an upstanding member carried on said frame in rear of said motor, cutting mechanism including a cutter chain driving 25 sprocket, feeding mechanism for feeding said frame bodily laterally along a mine face including a feed operating member and a worm disposed on said upstanding member and operatively connected to said feed 30 operating member, means for rotating said sprocket and said worm by power from said motor including a pinion on said armature shaft and a gear meshing with said pinion and disposed on said member above said 35 worm, and a second feed operating member rotatable by power from said motor at a different speed from said first mentioned feed operating member.

100. A room and pillar mining machine 40 slidable upon a mine bottom during cutting and including a machine frame, a motor thereon having its armature shaft rotatable on an axis extending longitudinally of said frame, an upstanding member carried on 45 said frame in rear of said motor, cutting mechanism including a cutter chain driving sprocket, feeding mechanism for feeding said frame bodily laterally along a mine face including a feed operating member and a 50 worm disposed on said upstanding member and operatively connected to said feed operating member through a worm wheel, means for rotating said sprocket and said worm by power from said motor including a pinion on said armature shaft and a gear meshing with said pinion and disposed on 55 said member above said worm and worm wheel, and a second feed operating member rotatable by power from said motor at a 60 different speed from said first mentioned feed operating member.

101. A room and pillar mining machine 65 slidable upon a mine bottom during cutting and including a machine frame, a horizontal motor thereon rotatable on an axis extend-

ing longitudinally of said frame, cutting mechanism thereon including a cutter chain driving sprocket, means for driving said sprocket from one end of said motor including a horizontally disposed bevel gear, mechanism for feeding said frame bodily laterally along the mine face including a feed operating member rotatable on a transverse axis and speed reducing driving connections between said bevel gear and said feed operating member including a plurality of operatively connected transverse members one of which is disposed beneath the plane of said bevel gear, and means for guiding said frame during its bodily lateral movement including a second feed operating member 70 coaxial with one of said transverse members. 75

102. A room and pillar mining machine 80 slidable upon a mine bottom during cutting and including a machine frame, a horizontal motor thereon rotatable on an axis extending longitudinally of said frame, cutting mechanism thereon including a cutter chain driving sprocket, means for driving said 85 sprocket from one end of said motor including a horizontally disposed bevel gear, mechanism for feeding said frame bodily laterally along the mine face including a feed operating member rotatable on a transverse axis and speed reducing driving connections 90 between said bevel gear and said feed operating member including a plurality of operatively connected transverse members one of which is disposed beneath the plane of said bevel gear, and means for guiding said frame during its bodily lateral movement including a second feed operating member 95 coaxially with one of said transverse members. 100

103. A room and pillar mining machine 105 slidable upon a mine bottom during cutting and including a machine frame, a horizontal motor thereon rotatable on an axis extending longitudinally of said frame, cutting mechanism thereon including a cutter chain driving sprocket, means for driving said sprocket from one end of said motor including a horizontally disposed bevel gear, mechanism for feeding said frame bodily laterally along the mine face including a feed operating member rotatable on a transverse axis, and speed reducing driving connections between said bevel gear and said 110 feed operating member including a plurality of transverse members one of which is disposed beneath the plane of said bevel gear, speed reduction mechanism between the same comprising elements carried by said members, and means for guiding said frame during its bodily lateral movement including a second feed operating member coaxial with one of said transverse members. 115

104. A room and pillar mining machine 120 slidable upon a mine bottom including a 125

motor, an upstanding member longitudinally spaced from said motor, a cutter chain driving sprocket longitudinally spaced from said member, lateral feeding mechanism including a member disposed transversely above said sprocket, a plurality of feed operating members adapted respectively to cooperate directly with flexible feeding portions and operatively connectible with said transversely disposed member, flexible feeding portions cooperating respectively with said feed operating members, and means for driving both said sprocket and said transverse member from said motor including driving means coaxial with said upstanding member.

105. A room and pillar mining machine 70
slidable upon a mine bottom including a motor, an upstanding member longitudinally spaced from said motor, a cutter chain driving sprocket longitudinally spaced from said member, lateral feeding mechanism including a member disposed transversely above said sprocket, a plurality of feed operating members operatively connectible therewith and respectively adapted to cooperate directly with flexible feeding portions, flexible feeding portions cooperating respectively with said feed operating members, and 75
means for driving both said sprocket and said transverse member from said motor including a bevel gear carried on said upstanding member.

106. A room and pillar mining machine 80
slidable on its bottom including a motor, an upstanding member longitudinally spaced from said motor, a cutter chain driving sprocket longitudinally spaced from said member, means for rotating said sprocket from said motor including a member coaxial with said upstanding member, and feeding mechanism likewise driven by said motor and including a member disposed in a horizontal plane above said sprocket, and 85
a plurality of feed operating members operatively connected therewith and each adapted to directly cooperate with a flexible feeding portion.

107. A room and pillar mining machine 90
including a machine frame, a motor thereon having its armature shaft rotatable on an axis extending longitudinally of said frame, an upstanding member carried on said frame in rear of said motor, cutting mechanism including a cutter chain driving sprocket, mechanism for effecting sumping of said cutting mechanism into a face including a pair of feed operating members rotatable on transverse axes and each adapted to cooperate directly with a flexible feeding portion, a rotatable gear on said upstanding member, operative connections between the same and said feed operating members, and means for rotating said sprocket and said rotatable gear by power from said motor including 95

a bevel pinion on said armature shaft and a bevel gear meshing with said pinion and disposed on said upstanding member above said rotatable gear.

108. A room and pillar mining machine 100
including a motor having its armature shaft rotatable on an axis extending longitudinally of the machine, cutting mechanism including a cutter chain driving sprocket, a driving gear therefor coaxial therewith, 105
feeding mechanism for sumping said cutting mechanism into a face and for feeding said machine bodily laterally along the mine face including a plurality of feed operating members each operable to effect winding in of 110
a flexible member associated therewith, a worm wheel and friction controlled planetary driving connections between said worm wheel and said feed operating members, and means for rotating said cutter chain driving 115
sprocket driving gear and said worm wheel by power from said motor including a driving pinion on said armature shaft, a gear meshing therewith and driven thereby, a shaft on which said last mentioned gear is 120
fixed, a worm on said shaft engaging said worm wheel, and a pinion on said shaft engaging said cutter chain driving sprocket driving gear.

109. A room and pillar mining machine 125
slidable upon a mine bottom during cutting and including a motor having its armature shaft rotatable on an axis extending longitudinally of the machine, cutting mechanism including a cutter chain driving 130
sprocket, a driving gear therefor coaxial therewith, feeding mechanism for sumping said cutting mechanism into a face and for feeding said machine bodily laterally along the mine face including a plurality of feed operating members, a worm wheel, multi-planet planetary driving connections between said worm wheel and said feed operating members, clutch mechanism coaxial with certain elements of said planetary driving connections, and means for rotating said cutter chain driving sprocket driving gear and said worm wheel by power from said motor including a driving pinion on said 135
armature shaft, a gear meshing therewith and driven thereby, a shaft on which said last mentioned gear is fixed, a worm on said shaft engaging said worm wheel, and a pinion on said shaft engaging said cutter chain driving sprocket driving gear.

110. A room and pillar mining machine 140
slidable upon a mine bottom during cutting and including a motor having its armature shaft rotatable on an axis extending longitudinally of the machine, cutting mechanism including a cutter chain driving sprocket, a driving gear therefor coaxial therewith, feeding mechanism for sumping said cutting mechanism into a face, feeding mechanism for feeding said machine bodily laterally 145
including a cutter chain driving sprocket, a driving gear therefor coaxial therewith, feeding mechanism for sumping said cutting mechanism into a face, feeding mechanism for feeding said machine bodily laterally 150

along the mine face including a feed operating member, a worm wheel and planetary driving connections between said worm wheel and said feed operating member, and 5 clutch mechanism coaxial with said planetary driving connections, and means for rotating said cutter chain driving sprocket driving gear and said worm wheel by power from said motor including a driving pinion 10 on said armature shaft, a gear meshing therewith and driven thereby, a shaft on which said last mentioned gear is fixed, a worm on said shaft engaging said worm wheel, and a pinion on said shaft engaging 15 said cutter chain driving sprocket driving gear, said worm being between the gear and pinion on the shaft.

111. A room and pillar mining machine 20 slidable upon a mine bottom during cutting and including a motor having its armature shaft rotatable on an axis extending longitudinally of the machine, cutting mechanism including a cutter chain driving sprocket, a driving gear therefor coaxial therewith, 25 feeding mechanism for effecting sumping of said cutting mechanism into a face and feeding of said machine bodily laterally along the face including a plurality of feed operating members rotating on transverse axes, a 30 worm wheel and planetary driving connections between said feed operating members and said worm wheel, and means for rotating said cutter chain driving sprocket driving gear and said worm wheel by power 35 from said motor including a driving pinion on said armature shaft, a gear meshing therewith and driven thereby, a shaft on which said last mentioned gear is fixed, a worm on said shaft engaging said worm 40 wheel, and a pinion on said shaft engaging said cutter chain driving sprocket driving gear.

112. A room and pillar mining machine 45 slidable upon a mine bottom during cutting and including a motor having its armature shaft rotatable on an axis extending longitudinally of the machine, cutting mechanism including a cutter chain driving sprocket, a driving gear therefor coaxial therewith, 50 mechanism for effecting sumping of said cutting mechanism into a face and feeding of said machine bodily laterally along the face including a plurality of feed operating members rotating on transverse axes, a 55 worm wheel and planetary driving connections between said worm wheel and feed operating members, frictional controlling means therefor, and means for rotating said cutter chain driving sprocket driving gear 60 and said worm wheel by power from said motor including a driving pinion on said armature shaft, a gear meshing therewith and driven thereby, a shaft on which said last mentioned gear is fixed, a worm on said 65 shaft engaging said worm wheel, and a pinion on said shaft engaging said cutter chain driving sprocket driving gear.

pinion on said shaft engaging said cutter chain driving sprocket driving gear.

113. A room and pillar mining machine 70 slidable upon a mine bottom during cutting and including a motor having its armature shaft rotatable on an axis extending longitudinally of the machine, cutting mechanism including a cutter chain driving sprocket, a driving gear therefor coaxial therewith, 75 mechanism for effecting sumping of said cutting mechanism into a face and feeding of said machine bodily laterally along the face including a plurality of feed operating members, a worm wheel and planetary driving connections between said worm wheel 80 and feed operating members, controlling means therefor including friction mechanism and jaw clutch mechanism, and means for rotating said cutter chain driving sprocket driving gear and said worm wheel 85 by power from said motor including a driving pinion on said armature shaft, a gear meshing therewith and driven thereby, a shaft on which said last mentioned gear is fixed, a worm on said shaft engaging said worm wheel, and a pinion on said shaft 90 engaging said cutter chain driving sprocket driving gear.

114. A room and pillar mining machine 95 slidable upon a mine bottom during cutting and including a motor having its armature shaft rotatable on an axis extending longitudinally of the machine, cutting mechanism including a cutter chain driving sprocket, a driving gear therefor coaxial therewith, 100 mechanism for effecting sumping of said cutting mechanism into a face and feeding of said machine bodily laterally along the mine face including a plurality of feed operating members, a driving shaft therefor, a 105 worm wheel and planetary driving connections between said worm wheel and driving shaft for said feed operating members, and mechanism controlling the operation of said feeding mechanism including a plurality of jaw clutches including elements slidable longitudinally of said driving shaft, and means for rotating said cutter chain driving sprocket driving gear and said worm wheel by power 110 from said motor including a driving pinion on said armature shaft, a gear meshing therewith and driven thereby, a shaft on which said last mentioned gear is fixed, a worm on said shaft engaging said worm wheel, and a pinion on said shaft 115 engaging said cutter chain driving sprocket driving gear.

115. In a mining mechanism, a machine 120 frame from which a cutter bar projects in a longitudinal direction during cutting, a cutter chain, a motor carried by said frame, driving connections between said chain and motor, and means for feeding said machine during cutting, including flexible means, 125 winding means including a plurality of feed 130

operating members rotating on transverse axes and each cooperating directly with said flexible means, and driving means for said winding means including a transverse shaft 5 parallel to the axes of said winding means, driving connections between the shaft and winding means, and driving connections between the motor and shaft including planetary gearing coaxial with the latter and driven by the motor.

116. In a mining mechanism, a machine frame from which a cutter bar projects in a longitudinal direction during cutting, a cutter chain, a motor carried by said frame, 15 driving connections between said motor and chain, and means for feeding said machine during cutting including flexible means, winding means including a plurality of feed operating members rotating on transverse 20 axes and each cooperating directly with said flexible means, and driving means for said winding means including a transverse shaft parallel to the axes of said winding means, driving connections between the shaft and 25 winding means, and driving connections between the motor and shaft including a friction brake and planetary gearing coaxial with the latter and driven by the motor and including a plurality of coaxial gears and a 30 plurality of planet gears cooperating therewith.

117. In a mining mechanism, a machine frame from which a cutter bar projects in a longitudinal direction during cutting, a cutter chain, a motor carried by said frame, 25 driving connections between said chain and motor, and means for feeding said machine during cutting including flexible means, winding means including a plurality of feed operating members rotating on transverse 30 axes and each cooperating directly with said flexible means, and driving means for said winding means including a transverse shaft parallel to the axes of said winding means, driving connections between the shaft and 35 winding means, and driving connections between the motor and shaft including planetary gearing coaxial with the latter and driven by the motor and including a plurality of coaxial gears and a plurality of planet gears cooperating therewith and a 40 clutch slidably longitudinally of said shaft.

118. In a mining apparatus, a machine frame provided with a cutter bar projecting longitudinally therefrom in fixed relation thereto during cutting, a motor on said frame having a longitudinally extending power shaft, a cutter chain on said bar, means for circulating the same including a gear journaled on a vertical axis at the rear of said motor, and means for feeding said frame including flexible portions, winding means including a plurality of feed operating members cooperating respectively one 55 with each of said flexible portions, and driv-

ing means for the latter including a transversely extending shaft to the rear of said vertical axis, power transmission connections between said shaft and motor including planetary gearing coaxial with said 70 shaft, and frictional controlling means.

119. In a mining mechanism, a frame carrying in rigid relation thereto a longitudinally projecting cutter bar, a cutter chain, a motor on said frame, driving connections between said motor and said chain, and feeding mechanism including flexible feeding means and winding means cooperating therewith including a pair of winding members rotatable on transverse axes, a 75 shaft parallel to said axes, driving connections between said shaft and members, and driving gearing for said shaft including orbitally moving gears fixed relatively to each other for rotation at equal angular rates on 80 a common axis, gears concentric with said shaft and with which said first mentioned gears mesh while traversing their orbits, friction means for holding one of said concentric gears against rotation, an operative connection between the other of said concentric gears and the transverse shaft, and means driven by said motor for causing said orbitally moving first mentioned gears to 85 travel around the first mentioned one of said second mentioned gears to cause the second mentioned one of said second mentioned gears to drive said transverse shaft.

120. In a mining mechanism, a frame carrying in rigid relation thereto a longitudinally projecting cutter bar, a cutter chain, a motor on said frame, driving connections between said motor and said chain, and feeding mechanism including flexible feeding means and winding means cooperating therewith, including a pair of winding members rotatable on transverse axes, a 100 shaft parallel to said axes, manually controllable driving connections between said shaft and member, and driving gearing for said shaft including orbitally moving gears fixed relative to each other for rotation on a common axis and at equal angular rates, gears concentric with said shaft and with which said first mentioned gears mesh while traversing their orbits, friction means for holding one of said last mentioned gears against 105 rotation, an operative connection between the other of said gears and the transverse shaft, and means driven by said motor for causing said first mentioned gears to travel around the first mentioned one of said second mentioned gears to cause the second mentioned of said second mentioned gears to drive said transverse shaft.

121. In a mining mechanism, a frame carrying in rigid relation thereto a longitudinally projecting cutter bar, a cutter chain, a motor on said frame, driving connections between said motor and said chain,

- and feeding mechanism including flexible feeding means and winding means cooperating therewith including a pair of winding members rotatable on transverse axes, a shaft parallel to said axes, driving connections between said shaft and member, and driving gearing for said shaft including orbitally moving gears fixed relative to each other for rotation on a common axis and at 5 the same angular rates, gears concentric with said shaft and with which said first mentioned gears mesh while traversing their orbits, friction means for holding one of said last mentioned gears against rotation, an 10 operative connection between the other of said gears and the transverse shaft, and means driven by said motor for causing said first mentioned gears to travel around the first mentioned one of said second mentioned 15 gears to cause the second mentioned of said second mentioned gears to drive said transverse shaft, and clutch mechanism movable longitudinally of said shaft.

122. A room and pillar mining machine 25 including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper end thereof meshing with said driving pinion, a cutter chain driving sprocket, a driving connection between said vertical shaft and said driving sprocket, and means 30 driven by said motor for feeding said machine bodily laterally along a mine face during cutting including a pair of feed operating members rotatable upon horizontal axes, a flexible feeding portion engaged directly by one of said feed operating members, another flexible feeding portion directly engaged by the other of said feed operating members, and actuating means for said feed operating members including a worm 35 rotatable upon a vertical axis.

123. A room and pillar mining machine including a motor having its armature shaft rotatable on an axis extending longitudinally of the machine, a bevel driving pinion upon the rear end of said shaft, a vertical shaft arranged to the rear of said armature shaft and carrying a bevel gear adjacent the upper end thereof meshing with said driving pinion, a cutter chain driving 40 sprocket, a driving connection between said vertical shaft and said driving sprocket, and mechanism driven by said motor for feeding said machine bodily laterally along a mine face during cutting including a pair of feed 45 operating members rotatable upon transversely extending axes, a flexible feeding portion engaged directly by one of said feed operating members, another flexible feeding portion directly engaged by the other of said feed operating members, and actuating

means for said feed operating members including a worm rotatable upon a vertical axis.

124. A room and pillar mining machine including a motor having its armature shaft 70 rotatable on an axis extending longitudinally of the machine, a bevel driving pinion upon the rear end of said shaft, a vertical shaft arranged to the rear of said armature shaft and carrying a bevel gear adjacent the upper 75 end thereof meshing with said driving pinion, a cutter chain driving sprocket, a driving connection between said vertical shaft and said driving sprocket, and mechanism driven by said motor for feeding said machine bodily laterally along a mine face including a pair of feed operating members rotatable upon horizontal axes, a flexible feeding portion directly engaged by one of said feed operating members, a second flexible portion directly engaged by the other thereof, and friction controlled actuating 80 means for said feed operating members including a worm rotatable upon a vertical 85 axis.

125. A room and pillar mining machine including a motor having its armature shaft rotatable on an axis extending longitudinally of the machine, a bevel driving pinion upon the rear end of said shaft, a vertical shaft 90 arranged to the rear of said armature shaft and carrying a bevel gear adjacent the upper end thereof meshing with said driving pinion, a cutter chain driving sprocket, a driving connection between said vertical shaft and said driving sprocket, and mechanism driven by said motor for feeding said machine bodily laterally along a mine face including a pair of feed operating members 95 rotatable upon transversely extending axes, a flexible feeding portion directly engaged by one of said feed operating members, a second flexible portion directly engaged by the other thereof, and friction controlled actuating 100 means for said feed operating members including a worm rotatable upon a vertical 105 axis.

126. In a mining mechanism, a frame carrying in rigid relation thereto a longitudinally projecting cutter bar, a cutter chain, a motor on said frame, driving connections between said motor and said chain, and feeding mechanism including a flexible portion and winding means cooperating therewith including a winding member 115 journaled on the frame, and driving gearing for said winding member including orbitally moving gears rotating at equal angular speeds and on a common orbitally moving axis, a plurality of coaxially arranged gears with which said first mentioned gears mesh while traversing their orbits, friction means for holding one of said coaxial gears against rotation, an operative connection between the other of said 120 125 130

coaxial gears and the winding member, and means driven by said motor for causing said orbitally moving gears to travel around the first mentioned one of said second mentioned 5 gears to cause the second mentioned one of said second mentioned gears to drive said winding member, a second flexible portion, and a second winding member cooperating therewith and journaled on said frame and 10 driven by said motor.

127. In a mining mechanism, a frame carrying in rigid relation thereto a longitudinally projecting cutter bar, a cutter chain, a motor on said frame, driving connections between said motor and said chain, and feeding mechanism including a flexible portion and winding means cooperating therewith including a winding member journaled on the frame, and driving gear- 15 ing for said winding member including orbitally moving gears rotating at equal angular speeds and on a common orbitally moving axis, a plurality of coaxially arranged gears with which said first mentioned 20 gears mesh while traversing their orbits, friction means for holding one of said coaxial gears against rotation, an operative connection between the other of said coaxial gears and the winding member, and means 25 driven by said motor for causing said orbitally moving gears to travel around the first mentioned one of said second mentioned gears to cause the second mentioned one of said second mentioned gears to drive said 30 winding member, a second flexible portion, and a second winding member journaled on a horizontal axis and driven by said motor.

128. In a mining mechanism, a frame carrying in rigid relation thereto a longitudinally projecting cutter bar, a cutter chain, a motor on said frame, driving connections between said motor and said chain, and feeding mechanism including a flexible portion and winding means cooperating therewith including a winding member journaled 35 on the frame, and driving gearing for said winding member including orbitally moving gears rotating at equal angular speeds and on a common orbitally moving axis, a plurality of coaxially arranged gears with which said first mentioned gears mesh while traversing their orbits, friction means for holding one of said coaxial gears against rotation, an operative connection between 40 the other of said coaxial gears and the winding member, and means driven by said motor for causing said orbitally moving gears to travel around the first mentioned one of said second mentioned gears to cause the second mentioned one of said second mentioned gears to drive said winding member, a second flexible portion, and a second winding member journaled in advance of said first mentioned winding member and driven 45 by said motor.

129. A mining machine comprising a frame slidable on the mine bottom and a projecting cutter bar, and means for feeding said frame and guiding the same during cutting and at other times including a plurality of flexible feeding portions disposable during cutting transversely of a face in opposite directions from the opposite ends of said frame, and feed operating and controlling means including a plurality of elements each rotatable by power and cooperating respectively with said flexible feeding portions, and driving means for said elements operable without reversal of said motor or change in the mode of direct co-operation of said portions with said elements to cause one of said elements to wind in one of said portions at a predetermined cutting speed, or to cause the other of said elements to draw in its cooperating flexible portion at a higher predetermined cutting speed or at a substantially higher predetermined machine moving speed which is greater than the maximum potential cutting speed of the machine under normal working conditions.

130. The combination with a mining machine slidable on a mine bottom during cutting, flexible machine feeding means, a feed operating member, a motor, variable speed reduction gearing connecting said motor and member, and friction clutch mechanism interposed between said reduction gearing and said feed operating member adjustable at will during the operation of said feed operating member.

131. The combination with a mining machine, of a feed operating member, a motor, variable speed reduction gearing for said feed operating member operative to effect driving thereof at different uniform speeds, friction clutch mechanism interposed between said gearing and said member adjustable at will during the operation of said feed operating member, and means for automatically maintaining such adjustments.

132. The combination with a mining machine, of a feed operating member, a motor, variable speed reduction gearing therefor adapted to drive said member at different uniform speeds, and friction clutch mechanism adjustable at will during operation of said feed operating member interposed between said gearing and said member and disposed coaxially with said member.

133. A mining machine slidable on a mine bottom comprising cutting mechanism including a projecting cutter bar and flexible feeding mechanism including a plurality of flexible feeding portions adapted to act on the opposite ends of the machine frame and having free extremities adapted for connection to fixed points, a motor operatively connected to said cutting mechanism, and means driven by said motor and cooperating with

- said flexible feeding mechanism to effect movement of said machine including means for winding in that flexible feeding portion which extends rearwardly from said machine
- 5 during a cut across a face automatically at a plurality of different predetermined speeds including a winding member, a horizontal transversely disposed shaft, means for rotating said shaft at a plurality of 10 different speeds proportional to said speeds of drawing in, and clutch means coaxial with said shaft and reciprocable longitudinally thereof to connect or wholly disconnect said winding member from said shaft.
- 15 134. The combination with a mining machine, of fast and slow speed drive gearing driven from a common source, a feed operating member connectible to said gearing for operation thereby at either speed, and a friction 20 clutch between said member and said gearing adjustable at will during operation of said feed operating member and operative to transmit power at either speed to said feed operating member.
- 25 135. The combination with a mining machine, of feed driving mechanism including reduction gearing, a feed operating member, and operative connections between the same including a plurality of clutches arranged 30 in series one operable to vary the speed of drive of said feed operating member and one adjustable during driving to vary the power transmissible and so disposed as to be subject to substantially equal forces tending to 35 cause it to yield irrespective of the feeding speed when the resistance to feeding is the same.
136. In a mining machine having cutting mechanism, the combination with feeding means, of mechanism for actuating said feeding means including a train, as respects cutting mechanism drive, peculiar to the actuation of said feeding mechanism and also including a yielding element and a supplemental 40 transmission connection automatically released by conditions of overload in the event of failure of said yielding element to yield.
- 45 137. In a mining machine having cutting mechanism, the combination with feeding means, of mechanism for actuating said feeding means including a train, as respects cutting mechanism drive, peculiar to the actuation of said feeding mechanism and including 50 a yielding element and a supplemental transmission connection automatically released by conditions of overload in the event of failure of said yielding element to yield.
- 55 138. In a mining machine having cutting mechanism, the combination with feeding means, of mechanism for actuating said feeding means including a train, as respects cutting mechanism drive, peculiar to the actuation of said feeding mechanism and including a yielding element, means for increasing the resistance to yielding opposed by said element, and an additional transmission connection automatically released by conditions of overload in the event of failure of said yielding element to yield.

positive driving connection automatically rendered inoperative by conditions of overload in the event of failure of said yielding element to yield.

138. In a mining machine having cutting mechanism, the combination with feeding means, of mechanism for actuating said feeding means including a train, as respects cutting mechanism drive, peculiar to the actuation of said feeding mechanism and including a yielding element, means for increasing the resistance to yielding opposed by said element, and an additional transmission connection automatically released by conditions of overload in the event of failure of said yielding element to yield.

139. In a mining machine having cutting mechanism, the combination with feeding means, of mechanism for actuating said feeding means including a train, as respects cutting mechanism drive, peculiar to the actuation of said feeding mechanism and including a friction device, and an additional transmission member automatically rendered inoperative by conditions of overload in the event of failure of said friction device to yield.

140. In a mining machine having cutting mechanism, the combination with feeding means, of mechanism for actuating said feeding means including a train, as respects cutting mechanism drive, peculiar to the actuation of said feeding mechanism and including an adjustable friction device, and an additional transmission member automatically rendered inoperative by conditions of overload in the event of failure of said friction device to yield.

141. The combination with a mining machine, of feeding mechanism including flexible feeding portions adapted to act on opposite sides of said machine, feed operating mechanism operative to draw in either portion at a cutting speed including drums respectively cooperating with said portions, and means on said machine for frictionally limiting or completely interrupting the paying out of one portion while drawing in the other.

In witness whereof, I have hereunto set my hand at Indianapolis, Indiana, this 20th day of April, A. D. one thousand nine hundred and sixteen.

FRANK CARTLIDGE.
